DISCHARGE RECTIFIER TUBE WITH
INDIRECTLY HEATED CATHODE

Palmer H. Craig, Shaker Heights, and John J. Glauber, Cleveland Heights, Ohio, assignors to Invex Corporation, a corporation of New York

Application May 31, 1940, Serial No. 338,194

8 Claims. (Cl. 250—27.5)

This invention relates to electronic tubes of the space discharge rectifier class, and particularly to such tubes having an indirectly heated cathode.

In an article published by Palmer H. Craig, in "Electronics," March 1933, at pages 70 to 72 inclusive, is illustrated and described a rectifier tube of this class, the tube of that article being therein named, Kathetron; and the tube of the present invention may be considered as an improvement of the Kathetron of that publication.

The tube of this invention, therefore, comprises in general, an evacuated envelope containing an anode, and an indirectly heated cathode, and ionizable gas at predetermined pressure; and, when control of the current flow through the tube is wanted, a control electrode or grid. In the preferred construction, the grid, when employed, is in the form of a loop or band externally encircling or embracing the envelope, but the grid may be of other forms, and may be disposed within the envelope.

It is therefore among the objects of the present invention:

To provide generally an improved electronic tube of the gaseous discharge rectifier class and of the type having a hot cathode;

To provide generally an improved electronic tube of the class referred to, and of the type having an indirectly heated cathode and a control electrode or grid;

To provide an improved construction of indirectly heated cathode for electronic tubes;

To provide for electronic tubes of the type having a cathode indirectly heated by electric current, improved means for reducing heat radiation from the heated parts of the cathode, whereby the necessary wattage to attain a desired cathode temperature may be minimized.

To provide, in an indirectly heated cathode of the type comprising a heated, two-dimensional metal surface having thermionic material thereon, an improved construction whereby a metal surface of great area may be contained in a small three-dimensional space;

To provide in a tube of the type referred to, an improved construction and arrangement of control grid;

To provide, in a tube of the evacuated-envelope directly-heated-cathode type, improved means for mounting and supporting the cathode structure on a pinch of the tube;

To provide, in a tube of the hot cathode gaseous discharge rectifier type having an evacuated

envelope, improved means for conducting the main discharge current through the cathode and out of the tube, and for conducting current for heating the cathode to and from cathode heating elements;

To provide an electronic tube of the space discharge rectifier class, constructed in an improved manner whereby improved qualities of cheapness of manufacture and reliability and efficiency in operation are attained.

Other objects will be apparent to those skilled in the art to which our invention appertains.

Our invention is fully disclosed in the following description taken in connection with the accompanying drawings, in which:

Fig. 1 is a front elevational view of a tube embodying our invention with a part of the envelope broken away to disclose internal parts of the tube;

Fig. 2 is a view to enlarged scale partly in longitudinal section of a cathode of the tube of Fig. 1;

Fig. 3 is a view taken from the plane 3—3 of Fig. 2;

Fig. 4 is a view to reduced scale taken in the direction of the arrow 4 of Fig. 2;

Fig. 5 is a view, in some respects diagrammatic, illustrating the internal construction of the cathode of Fig. 2;

Fig. 6 is a cross-sectional view taken from the plane 6—6 of Fig. 2;

Fig. 7 is a diagrammatic view illustrating an electric circuit system which may be employed with the tube of the other figures.

Referring to the drawings, we have shown in elevation in Fig. 1, a tube embodying our invention in a preferred form and comprising a glass envelope 1, having on the lower end thereof a metal plug base 2 of the prong type provided

with three insulated prongs 4, 5 and 6, and having above the base a pinch 7 in which are sealed terminal conductors connected to the prongs in the usual manner, and to be referred to. The envelope has been evacuated and contains an ionizable gas such as argon therein at a predetermined pressure to be referred to.

In the upper end portion of the envelope 1 is an anode 8 electrically connected to an external terminal 9 in the usual manner. The anode may be of graphite, or of molybdenum, or of carbonized nickel, or may be of other materials such as have been used for the anodes of tubes of the hot cathode rectifier type.

At 10 is shown generally a cathode of the indirectly heated type. Structurally it comprises,

see Fig. 2, a pair of posts 11 and 12 extending upwardly from the pinch and spot welded to opposite portions of a main outer cathode cylinder 13 of nickel or other suitable metal. For convenience of assembling, the posts are in two parts, the lower parts 14 and 15, being mounted and sealed in the pinch 7, and having sleeves 16 and 17 welded thereto, and the upper parts, the posts 11 and 12 proper, being telescoped into the sleeves 16 and 17 to mount the posts on the pinch.

By this means, the cathode structure proper, including the posts 11 and 12, may be separately constructed, and the post parts 14 and 15 with their sleeves 16 and 17, may be mounted in the pinch 7; and subsequently the cathode structure may be mounted on the pinch by telescoping the posts proper 11 and 12 into the sleeves 16 and 17. Inasmuch as the posts proper 11 and 12 may, if desired, be themselves extended to include the parts 14 and 15 and be integral therewith and mounted in the pinch, hereinafter the posts, including the sleeves 16 and 17 and the post parts 14 and 15, are referred to as the posts 11 and 12, for convenience of description.

Within the cylinder 13 and co-axial therewith is an inner metal tube 18, see Figs. 5 and 6. A plurality of heater tubes 19, 20, 21, and 22, are disposed between the inner wall of the cylinder 13 and the outer wall of the inner tube 18 and spot-welded to the tubes 13 and 18 at opposite points on the heater tubes. The cross-sectional form of the inner tube 18 is preferably polygonal, although this is not essential, and it may be of square cross-section as shown, or of hexagonal or octagonal section, and the planar portions of such a polygonal tube provide convenient means for positioning the heater tubes 19 to 22 and the outer tube 13 around a common axis of the cathode as illustrated.

A post 23 mounted in and extending upwardly from the pinch 7 has its upper end disposed in a socket or thimble 24 secured by welding to a lower outer sheet metal head 25 having an upwardly extending skirt 26 at its periphery. A lower inner sheet metal head 27, likewise provided with a peripheral skirt 28, rests upon the head 25 and is preferably spaced therefrom to reduce heat conduction through the head 25, by means of pimples or bosses 29 pressed outwardly downwardly from the metal of the head 27 and resting upon the head 25.

Perforations 30-30 are provided in the head through which the said posts 11 and 12 extend and thereby the heads are positioned relative to the posts.

The outer tube 13, inner tube 18, and heater tubes 19 to 22, rest upon the inner head 27 or terminate adjacent thereto, and the head 25 preferably rests upon the upper ends of the sleeves 16 and 17 to further support the heads.

An upper head 31 is provided having a large central perforation 32, and a downwardly extending peripheral skirt 33 and is secured to the upper end portions of the posts 11 and 12 by tongues 34-34 bent upwardly from the periphery of the perforation 32, and spot welded to the posts 11 and 12 at their upper end portions. The perforation 32 in the upper head is preferably of approximately the size and shape of the outer tube 13 and aligned therewith.

Heat insulating tubes or shields 35 and 36, of low heat-conducting material, such for example as lava, are provided mounted independently of the cathode proper above described. They rest

upon the lower heads 27 and 25 respectively and are axially centered thereon by engaging within the skirts 28 and 26 respectively of the lower heads. At their upper ends the heat insulating shield 36 is engaged within the peripheral skirt 33 of the upper head 31, and the shield 35 is positioned by prongs 37 bent downwardly from the head 31. The inner shield 35 is spaced from the tube 13 and entirely out of contact therewith, and the outer shield 36 is spaced from the inner shield, thereby providing complete tubular heat insulating spaces therewithin.

Below the cathode proper thus constructed, a ring 38 is supported by being welded to a post 39 mounted in the pinch. Heating filaments 40, 41, 42, 43, arranged to be electrically heated, and wound into helical form, are disposed axially of and within the heater tubes 19 to 22, their lower ends being axially extended through perforations in the lower heads and spot welded to the ring 38, and their upper ends being axially extended out of the cathode proper and spot welded to tongues 44 extending upwardly from the upper head 31 at the periphery of the perforation 32.

A reflector 45 of nickel or like metal and in the form of a disc, is mounted above the cathode proper by tongues 46-46 bent downwardly from opposite edges thereof and spot welded to the upper ends of the posts 11 and 12, preferably to the tongues 34-34.

The reflector 45 reduces heat radiation axially away from the cathode proper, and together with the heat insulation effected by the shields 35 and 36 as described reduces the total radiation of heat and enables the filaments 40 to 43 to maintain the desired temperature of the cathode at the expenditure of correspondingly small wattage.

By the construction above described, a great sheet metal cathode surface area is provided in small three-dimensional space, and this surface area is coated with thermionic material such as barium or strontium carbonate or a mixture thereof, which, when the cathode surfaces are heated in the process of evacuating the tube as is customary (either inductive, by means of a high frequency coil, or conductively, by current caused to flow into and out of the structure by way of the posts 11 and 12, or by both means), is converted into strontium or barium oxide or a mixture thereof. This oxide coating of thermionic material is shown in Fig. 6 at 47 on the inner wall of the outer tube 13, and at 48 on the outer walls of the heating tubes 19 to 22, and at 49 on the outer wall of the inner tube 18, and at 50 on the inner wall of the tube 18. The electric circuit to heat the filaments is from a wire 51 to the post 39, see Fig. 2, to which is connected the ring 38, thence to all of the filaments 40 to 43 in parallel to the upper head 31, and thence through the post 11 and out by a wire 52.

A getter pellet is shown at 53, Fig. 1, mounted on a wire 54 welded to one of the sleeves, such for example as the sleeve 17, which is flashed in the usual manner during the usual process of evacuating the envelope, which may be employed.

The main circuit through the tube is from the anode connection 9 to the anode 8, through the gase as a discharge arc to the cathode outer tube 13, and thence by post 12 to a wire 55. The wires 51, 52 and 55, shown best in Fig. 2, are, as will be understood from prior tube practice, connected to the insulated prongs 4, 5 and 6 of Fig. 1.

As referred to above, the envelope may be evacuated by the well known process, including heating of the internal structural parts and flashing of the getter; and then gas, such as argon, is introduced at the desired pressure.

The general operation of the tube, as above described, is that well known of tubes of this class. The filaments heat the said tubes and their thermionic coatings, causing the latter to emit electrons, and these electrons ionize the gas within the envelope causing it to emit other electrons; and when potential is impressed upon the anode and cathode, and the anode is positive with respect to the cathode, a flow of the electrons occurs toward the anode, and electric current is considered conventionally as flowing from the anode to the cathode in the nature of a space discharge, and in amount depending upon the potential and the external resistance of the circuit.

A control electrode or grid 56, in the form of an external band-grid outside of and embracing or encircling the envelope 1, is provided, and it may be variously constructed. It may be in the form of a separate metal detachable wire or band of metal; or a band of metal mesh; but preferably we provide a band which in effect is sealed into the material of the outer wall of the envelope. The preferred process for applying such a band grid is that used in ornamenting glass ware with bands or the like of platinum. A so-called "liquid platinum" is painted in the form of a band on the outer wall of the envelope and over an outwardly extending nipple 57. The glass and the band are then heated and the band fuses into the glass surface under the band, the band having finally the appearance of being a part of the glass. A band thus made is conductive, and a terminal 58 is mounted on that part of the band covering the nipple by which electric connection can be made to the grid. The band being fused to the glass cannot shift. If the band 56 be considered as a separate detachable metal band, its conformity with the glass projection or nipple 57 interlocks it with the envelope and prevents it from shifting out of position axially of the envelope.

The grid is shown in Fig. 1 as disposed between the cathode and anode which is its preferred position.

When a tube constructed as above described is put into operation by heating the filaments thereof, discharge tends to flow in the form of an arc discharge from the anode 8 to the cathode 10 when they are subjected to potential and the anode is positive with respect to the cathode. If the grid be energized at a suitable potential, and negative with respect to the anode when it is positive with respect to the cathode, its action will prevent flow of discharge current through the tube, and lower degrees of energization of the grid will permit the flow in inversely corresponding amperage.

Hereinafter when the anode is referred to as of positive sign, it is with the meaning that it is positive with respect to the cathode; and when the grid is referred to as negative it is with the meaning that it is negative with respect to the anode when the latter is positive.

When the potential impressed upon the anode and cathode is alternating, the flow of current occurs only during those half waves in which the anode is positive as is well known, and, even without energization of the grid, is automatically interrupted in each half cycle in which the anode is negative; and therefore with alternat-

ing current, such a tube admits of control of the effective amperage flowing, by suitably energizing the grid, inasmuch as the grid can at any time be energized to cut off the flow of current by preventing its starting on the next succeeding positive half cycle; or by lower degrees of energization can control the effective amperage by delaying the time of starting in each positive half cycle.

Because of the greater usefulness of the tube with alternating current, as above indicated, it is considered herein only in that usage.

A more stable and otherwise satisfactory control of the amperage flowing through the tube may be effected if alternating voltage is impressed upon the grid and out of phase with that impressed upon the anode and cathode. To this end the control of the effective amperage by corresponding energization of the grid may be effected by varying the phase relationship between the grid energization and the potential impressed upon the anode; but we prefer to effect this control by utilizing a fixed angular phase displacement of the grid energization and varying the potential on the grid at this phase displacement. We have found that a suitable phase displacement is approximately 135 degrees lag of band grid negative potential behind the anode positive potential, and this fixed-angle, variable-potential grid control is fully illustrated and described in the patent to Palmer H. Craig, No. 2,001,836, issued May 21, 1935, to which reference may be had.

In Fig. 7 is illustrated a representative circuit for effecting this type of control with a tube such as is described above. In this figure, at 1 is shown the envelope, at 8 the anode, at 56 the grid, at 11 and 12 the posts supporting the cathode 13, 18, 20 to 22, heated by filaments 40 to 43. Supply mains 59 and 60 energize the primary 61 of a transformer, the secondary 62 of which supplies alternating current at suitable voltage, such for example as five volts, to the above described heating circuit comprising the wires 51 and 52. The supply mains also energize the primary 63 of a transformer having a secondary 64, connected in a loop circuit with a resistor 65 and a condenser 66, the said loop circuit being also connected to the supply main 59 by a wire 67.

The grid 56 is connected at 68 to the resistor 65 by an adjustable rheostat type of connection for adjusting the potential of the grid 56, the circuit for the grid being considered as from the connection 68 to the grid thence to the anode 8, through the wire 67 and back to a part of the resistor 65. The condenser 66 may be adjusted to cause the negative potential on the grid 56 to be out of phase with the potential on the anode 8 as described and at this fixed phase displacement, which as stated above, is preferably of the order of 135 degrees behind the anode potential, the actual potential on the grid 56 may be adjusted by the adjustable connection 68.

As illustrative of suitable quantities for parts of the circuit of Fig. 7, we may add here that for a rectifier as described above having a continuous main current carrying capacity of $2\frac{1}{2}$ amperes, the capacity of the condenser 66 may suitably be .019 microfarad and the resistance of the resistor 65 may suitably be of the order of 150,000 ohms, and the voltage across the resistor provided by the transformer secondary 64 may suitably be 600 volts for supply mains at 110 volts

60 cycles. With the fixed phase displacement referred to, the grid connection at 68 may be adjusted from for zero grid potential, at which the full 2½ amperes will flow in the main load circuit, from the anode to the cathode of the tube; and that if the potential or the grid 56 be adjusted to raise it, the effective amperage in the load circuit will be decreased, and at approximately 450 volts on the grid 56, the main current will be completely cut off. It follows that the effective current supplied to the load of Fig. 7 can be adjustably varied from zero to the maximum capacity of the tube by adjusting the connection at 68.

As mentioned hereinbefore, rectifier tubes of the gaseous discharge type are known containing a gas such as argon in the envelope. In the above described tube, we also prefer to employ as stated a gas such as argon, but we have found that the pressure of the gas within the envelope should be taken into account. For any pressure utilized the grid energization should correspond, when the control of the current flow by the grid energization is wanted. If a low gas pressure is used, the grid voltage to normally cut off current flow is lower, and if the pressure is high, it is higher.

We have found that, taking into account the voltage drop and loss of energy through the tube, and the optimum control conditions for varying the current by the grid from zero to the maximum discharge current of the tube, a suitable pressure is of the order of 90 to 110 microns of mercury, and we therefore prefer to use that pressure of argon in the tube for ordinary application.

In alternating current installations in which variation of the flow of current through the tube is not wanted, and all that is wanted is initiation and interruption of the current by grid control, the negative grid may be energized with a phase displacement of 180 degrees with respect to the positive anode. Also while we have described the control of variation of the current flow through the tube by utilizing a negative grid energized out of phase with the positive anode and having the grid potential adjusted by a rheostat at a fixed phase displacement, it is to be understood that our invention may likewise be practiced by the above mentioned system which adjusts the phase displacement of the grid energization with respect to the anode potential. It is believed that these alternative methods of practicing our invention will be understood from the more complete description of the preferred methods without further illustration or description herein.

We have described our tube herein as simply a tube of the rectifier class, the discharge amperage through which may be controlled by controlling the grid voltage. The tube of the construction illustrated and described herein, but operating as a light responsive or photo-electric tube, constitutes the subject matter of the co-pending application of Palmer H. Craig and Lester C. Herman, Serial Number 334,846, filed May 13, 1940, assigned to the same assignee as the present application, the tube of said co-pending application being named Photodyne. When the grid is not utilized, or, if provided, when it is not energized, the tube operates as a simple rectifier tube.

Our invention is not limited to the exact details of construction illustrated and described. Changes and modifications may be made within

the scope of our invention without sacrificing its advantages and within the scope of the appended claims. For example the tube of our invention may be used in multiple back-to-back arrangement, to pass a full wave of alternating current.

We claim:

1. An indirectly heated cathode structure comprising a metal tube of polygonal cross section, and a plurality of metal tubes lying respectively upon the planar surfaces of the polygonal tube, and an enclosing metal tube telescoped over the plurality of metal tubes, and a coating of thermionic material on at least some of the surfaces of the tubes, and heating filaments disposed coaxially of and within the said plurality of metal tubes.
2. An indirectly heated cathode structure comprising an outer sheet metal cathode tube, a pair of posts secured to opposite portions of the sheet metal tube, a group of sheet metal tubes within the outer sheet metal tube, thermionic coatings on the outer walls of the group of tubes and on the inner wall of the outer tube, a plurality of heaters within at least some of the tubes of the group, and electrically connected in parallel at one end to a post, and at the other end electrically connected to a common conductor.
3. An indirectly heated cathode structure comprising an inner metal tube, a plurality of metal tubes thermo-conductively engaged with the outer surface of the inner tube, and spaced from each other, an outer metal tube telescoped over and thermo-conductively engaged with the outer walls of the plurality of tubes thereby providing a plurality of passages the walls of which are walls of the inner, outer and plurality of tubes, a coating of thermionic material on the walls of the passages, and heating means for heating the walls of the passages.
4. An indirectly heated cathode structure comprising an inner metal tube, a plurality of metal tubes thermo-conductively engaged with the outer surface of the inner tube, and spaced from each other, an outer metal tube telescoped over and thermo-conductively engaged with the outer walls of the plurality of tubes thereby providing a plurality of passages the walls of which are walls of the inner, outer and plurality of tubes, a coating of thermionic material on the walls of the passages, and heaters disposed coaxially within the plurality of tubes respectively for heating the walls of the passages.
5. An indirectly heated cathode construction comprising a pair of spaced-apart sheet metal tubes, a heater extending axially within each tube and spaced from its inner wall, a walled passageway between the tubes the outer walls of said tubes being walls of said passageway and a thermionic coating on the passageway walls.
6. An indirectly heated cathode construction comprising outer and inner coaxial tubes and an intermediate tube thermo-conductively engaged with the outer and inner tubes, a thermionic coating on the inner and outer surfaces of the outer and inner tubes respectively and on the outer wall of the intermediate tube and a heater extending axially within the intermediate tube.
7. An indirectly heated cathode construction comprising upper and lower sheet metal heads, an outer, an inner and a plurality of intermediate sheet metal tubes between the heads disposed to provide walled passages between adjacent in-

termide tubes, the passage walls being coated with thermionic material, heating elements within the intermediate tubes for heating the coated walls, and a tubular wall of heat insulating material surrounding and spaced from the outer sheet metal tube and supported by the said heads.

8. An indirectly heated cathode construction comprising a pair of spaced apart supporting posts, upper and lower sheet metal heads supported by the posts, an outer tube between the heads, a plurality of sheet metal tubes within the outer tube spaced to provide walled passages

5 therebetween, the walls of the passages being coated with thermionic material, heating means for heating the coated walls, a tubular wall of heat insulating material surrounding and spaced from the outer tube and supported between the heads, an opening in the upper head aligned with the outer tube and a heat reflector supported in axially spaced relation with respect to and transversely substantially coextensive with the opening in the upper head.

PALMER H. CRAIG.
JOHN J. GLAUBER.
